UNITED STATES PATENT OFFICE

121,325

DESIGN FOR A SCOOTER SLED

James Wendell Rawlings, Jacksonville, Ill.

Application April 25, 1940, Serial No. 91,952

Term of patent 14 years

To all whom it may concern:

Be it known that I, James Wendell Rawlings, a citizen of the United States, residing at Jacksonville, in the county of Morgan, and State of Illinois, have invented a new, original, and ornamental Design for a Scooter Sled, of which the following is a specification, reference being had to the accompanying drawing, forming part thereof.

I claim:

The ornamental design for a scooter sled, as shown.

JAMES W. RAWLINGS.
